Application October 26, 1944, Serial No. 560,492

9 Claims. (Cl. 271—62)

1

This invention relates to sheet feeders and more particularly to pile or sheet supply elevating or moving mechanism and control means therefor.

One object of the present invention is to provide a sheet feeder having novel means for intermittently operating the pile or sheet supply elevating or moving mechanism.

Another object of the invention is to provide a sheet feeder having novel means of smooth and reliable action for controlling the operation of the pile or sheet supply elevating or moving mechanism, and which is readily adjustable while the feeder is in operation to vary the feeding-in level of the pile or sheet supply to suit different stock conditions.

Another object is to provide a sheet feeder having novel mechanism for electrically controlling the operation of the pile or sheet supply elevating or moving means.

A further object is to provide a sheet feeder having novel mechanism for rendering the pile or sheet supply elevating or moving means intermittently effective, and wherein the usual foot clamp for holding the second sheet on the pile or supply against movement is utilized as the pile or sheet supply height testing member or feeler to control the operation of said mechanism.

The above and further objects and novel features of the present invention will more fully appear from the following detail description when the same is read in connection with the accompanying drawings. It is to be expressly understood, however, that the drawings are for the purpose of illustration only, and are not intended as a definition of the limits of the invention, reference for this latter purpose being had primarily to the appended claims.

In the drawings, wherein like reference characters refer to like parts throughout the several views,

Fig. 1 is a vertical longitudinal sectional view of a sheet feeder embodying the present invention and including a pile elevator, said view being taken on the line 1—1 of Fig. 2 looking in the direction of the arrows;

Fig. 2 is a front elevation of the sheet feeder shown in Fig. 1 with parts omitted for purposes of clearer illustration;

Figs. 3 and 4 are enlarged detail side elevations of pile elevator control means;

Fig. 5 is a top plan view, partly in section, of the control means shown in Fig. 3; and

Fig. 6 is a vertical transverse sectional view on the line 6—6 of Fig. 3.

2

Referring to the drawings, 10 and 11 indicate the main side frames and 12 and 13 indicate auxiliary side frames of a sheet feeder on which are mounted the various movable parts of the feeder, as well as certain stationary parts thereof. The frames 10 and 11 are connected together by a front apron or plate 14 bolted or otherwise suitably secured to said frames (Figs. 1 and 2). Extending transversely of the feeder 10 and journaled in suitable bearings in frames 10, 11 and in apron 14 is a shaft 15 having fixed on its opposite ends winding drums 16. Anchored to each drum 16 are corresponding ends of cables 17 and 18 which extend upwardly therefrom at 15 opposite sides of the feeder and pass over sheaves 19 journaled on frames 10, 11. From sheaves 19 the cables 18 extend rearwardly and pass around sheaves 20 also journaled on frames 10, 11 (Fig. 1). Cables 17 and 18 then extend downwardly from sheaves 19 and 20, respectively, and have their lower free ends connected to the front and rear ends, respectively, of pile elevator side bars 21 adapted to receive and support a pile board 22 and pile of sheets 23 (Fig. 1). Shaft 25 15 is intermittently rotated during the operation of the feeder by mechanism to be hereinafter described and which acts to raise the pile elevator step by step in order to maintain the top of the pile 23 at a proper level for accurate separation 30 and feeding of the sheets one after another therefrom. During upward movement of the elevator the front edge of the pile 23 is guided by spaced vertical guides 24 (Fig. 1) supported in any suitable manner on tie plate 14.

The sheets are separated one after another from the top of pile 23, and may be forwarded therefrom either singly in spaced relation, or in the form of a continuous stream of underlapped sheets. As herein shown, separation of the sheets 40 is effected by suction devices 25 (Figs. 1 and 2) of any suitable construction which are adapted to engage opposite rear corner portions of each successive sheet and lift the rear edge thereof above the level of the pile in a manner well understood in the art, therefore needing no detail illustration and description herein. Vacuum is created in suction devices 25 at predetermined intervals through flexible conduits 26 which are connected with said devices and with a suitable 45 valve mechanism (not shown) that, in turn, is connected with a vacuum pump (not shown) or other suitable source of vacuum.

After each sheet is separated and lifted at the rear thereof by suction devices 25 and while it 55 is being advanced by the sheet forwarding devices

hereinafter described, the sheet is wended from below to completely separate the same from the next underlying sheet by sheet winding devices which also act as foot clamps or hold downs and are preferably constructed, mounted and operated as follows. Arranged at the rear and opposite sides of the feeder are foot clamp housings 27 each comprising a main housing member 28 and a cover plate 29 removably secured thereto (Figs. 1 and 2). Housings 27 are mounted on and capable of adjustment along a pair of transverse shafts 30 having their opposite ends secured in brackets 31 and 32 that are supported on and movable along the tops of frames 10 and 11. Each housing 27 is secured in its various positions of adjustment by a clamp screw 33 threaded in the cover plate 29 and engaging one of the shafts 30. Extending transversely of the feeder through housings 27 and journalled in suitable bearings in said housings and in brackets 31 and 32 is a cam shaft 34 which is driven from any suitable source of power, for example, the printing press or other machine with which the feeder is associated. An additional support and bearing for cam shaft 34 is provided by a center bracket 35 (Fig. 2) secured to shafts 30.

Disposed within each housing 27 and keyed on cam shaft 34 is a cam 36 (Fig. 1) engaging a roller 37 journalled on one arm 38 of a bell crank lever 39 having another arm 40 projecting forwardly of the housing 27 through a suitable opening in the housing member 28 thereof. Bell crank 39 is secured to a short sleeve 41 (Figs. 1 and 2) journalled in suitable bearings in housing member 28 and cover plate 29. Roller 37 is biased toward cam 36 by a pull spring 42 having one end connected to arm 38 and the opposite end connected to housing member 28. Pivots connected at 43 to arm 40 is a cam link 44 having a closed cam groove 45 cooperating with a roller 46 journalled on an arm 47 formed integrally with housing member 28. Secured to or formed integrally with link 44 is an arm 48 in which is adjustably secured a downwardly and forwardly extending hollow foot clamp 49.

Through the combined actions of bell cranks 39 and cam grooves 45 in links 44, effected by the springs 42 and cams 36, the arms 48 are moved downwardly and upwardly and at the same time swung about the pivots 43 clockwise and counter-clockwise, respectively, once during each cycle of operation of the feeder. This results in a downward forward movement, and a backward upward movement of the foot clamps 49, the downward forward movement being so timed that it occurs after the sheet is lifted, resulting in engagement of said foot clamps with the top of the pile beneath the lifted sheet to wind and completely float the latter, and to prevent displacement of the underlying sheet while the lifted sheet is being wended and forwarded. Air under pressure is delivered to foot clamps 49 through flexible conduits 50 (Fig. 1) which are connected with said foot clamps and with a suitable valve mechanism (not shown) that is, in turn, connected with a suitable source of compressed air.

When the foot clamps 49 are engaged with the top of the pile 23 beneath the lifted sheet as aforesaid, and while air blasts are directed forwardly beneath said sheet, the latter is gripped at the rear thereof by sheet forwarding devices, whereupon the sheet is released by the suction devices 25 and forwarded by the sheet forwarding devices from the pile to conveying means hereinafter referred to. The air blasts through

foot clamps 49 are then cut off whereupon said foot clamps are moved rearwardly and upwardly for repetition of the cycle and operation on the next sheet.

5 The sheet forwarding devices may be of any type, but as herein shown, are of the suction type and indicated generally at 51 (Figs. 1 and 2). The latter are carried in arms 52 fixed on a rock shaft 53 which extends transversely of the feeder and is journalled in suitable bearings in brackets 31, 32 and 35. Shaft 53 is actuated from cam shaft 34 by suitable connections (not shown) to swing the suction devices 51 rearwardly to engage the lifted and wended sheet, and then forwardly to forward the engaged sheet from the pile. Vacuum is created and broken at predetermined intervals in the suction devices 51 to cause the latter to grip and release each lifted and forwarded sheet, through flexible conduits 54 which are connected with said devices and with a suitable valve mechanism (not shown).

Each sheet gripped by the suction devices 51 is forwarded thereby from the pile and delivered to conveying means indicated generally at 55. The conveying means 55 are driven by any suitable mechanism either at slow speed to enable lapping of the sheets thereon and to advance a stream of the lapped sheets to the printing press or other machine, or at fast speed to advance the sheets singly in spaced relation to said press or machine, as well understood in the art. Upon delivery of each sheet to the conveying means 55 by the suction devices 51, vacuum is broken in said devices which then swing rearwardly to engage the next previously separated and wended sheet.

During normal operation of the feeder the shaft 15 and drums 16 thereon are operated intermittently to raise the pile elevator and pile of sheets 23 at suitable intervals. As herein shown, the intermittent operation of the pile elevator is effected by mechanism comprising a cam 56 (Figs. 1 and 2) fixed on a transversely extending cam shaft 57 which is journalled in suitable bearings in frames 12, 13, and is driven from the same source of power that drives the hereinbefore described cam shaft 34. Cam 56 engages a roller 58 journalled on a cam strap 59 extending over shaft 57 and pivotally connected as at 60 with a pawl carrier 61. Roller 58 is biased toward cam 56 by a pull spring 62 having one end connected at 63 with pawl carrier 61 and the opposite end connected to an arm 64. The latter is bolted to a bracket 65 formed integrally with apron 14.

55 Pawl carrier 61 is preferably mounted for oscillating movement on the hub 66 (Figs. 1 and 2) of a clutch part 67 which is loosely mounted on a short transverse shaft 68 and cooperates with a clutch part 69 that is fixed on said shaft. Shaft 68 is journalled in suitable bearings in frame 11, plate 14 and bracket 65. Pivoted at 70 on pawl carrier 61 is a pawl 71 adapted to continuously engage a ratchet 72 fixed on hub 66 of clutch part 67. The clutch, comprising parts 67 and 69, is of well known construction, and is provided to enable disconnecting of the pawl and ratchet mechanism from shaft 68 and rotation of the latter by separate means (not shown) to rapidly lower and raise the pile elevator for loading and 70 reloading purposes. The clutch parts 67, 69 are normally engaged, and may be disengaged by any suitable means, such as, for example, a spool-like member 73 operated in any suitable manner.

Fixed on shaft 68 and adjacent ratchet 72 is a small spur gear 74 (Fig. 2) which meshes with

a large spur gear 15 (Figs. 1 and 2) that is fixed on a short transverse shaft 16 journalled in suitable bearings in plate 14 and bracket 65. Shaft 16 has also fixed thereon a small spur gear 17 meshing with a large spur gear 18 fixed on one end of a short transverse shaft 19 journalled in suitable bearings in plate 14 and bracket 65. Fixed on the opposite end of shaft 19 is a small spur gear 20 (Fig. 2) which meshes with a large spur gear 21 that is fixed on the shaft 15. Shaft 15 also extends through bracket 65 which provides an additional bearing and support for said shaft. Through oscillation of pawl carrier 61 by cam 56 and spring 62, and engagement of pawl 71 with ratchet 72, the shaft 15 and winding drums 16 thereon are thus intermittently rotated through the described gearing between said shaft and shaft 68, thereby imparting step by step elevation to the elevator and pile of sheets thereon. A retaining pawl 82 (Fig. 1) pivoted at 83 on bracket 65 is engaged with ratchet 72 to hold the latter and shaft 68 against return movement as pawl carrier 61 is returned for the pawl 71 to engage with another tooth on said ratchet.

Novel means are provided for electrically controlling the step by step elevation of the pile elevator and pile of sheets thereon as the sheets are separated and fed from the top of said pile by the described separating and forwarding devices, to keep the top of the pile at a predetermined level for action thereon by said devices. As herein shown, said control means preferably comprise a controlled member in the form of a latch 84 (Figs. 1 and 2) fixed on a short transverse shaft 85 journalled in suitable bearings in frame 13 and bracket 65. Latch 84 extends forwardly above cam strap 59 and is adapted to normally engage the bevelled forward end of a hardened steel block 86 (Fig. 1) secured to the upper surface of said cam strap. Engagement of latch 84 with block 86 holds cam strap 59 against return movement by spring 62, thus preventing roller 58 from following the low part of cam 56 and operation of pawl carrier 61 to engage pawl 71 with the next tooth on ratchet 72. The high part of cam 56 is so proportioned that upon engagement of the same with roller 58 during each cycle of operation a slight rearward movement is imparted to cam strap 59 to free latch 84 for disengagement from block 86 in a manner herein-after described.

Fixed on shaft 85 adjacent frame 13 is a forwardly extending arm 87 (Figs. 2 and 4) to which is pivotally connected at 88 the lower end of a vertical link 89. The upper end of link 89 is pivotally connected at 90 with the core 91 of a solenoid 92 that is bolted to the adjacent frame 13. When the solenoid 92 is energized as hereinafter described, core 91 is drawn upwardly and thus rocks shaft 85 through the described connections therefor with said core, whereupon latch 84 is raised out of engagement with block 86 on cam strap 59. The latter is then free to follow the low part of cam 56 and operate pawl carrier 61 to engage pawl 71 with the next tooth on ratchet 72, and thereafter partially rotate said ratchet and shaft 68 upon continued rotation of said cam to raise the pile elevator and pile of sheets as hereinbefore described. When solenoid 92 is deenergized, core 91 and latch 84 drop by gravity so that the latter is again positioned in the path of return movement of block 86 on cam strap 59 and prevents said strap from swinging pawl carrier 61 to enable pawl 71 to further raise the elevator and pile of sheets thereon.

Extending transversely of the feeder at the rear and one side thereof is a square bar 93 (Figs. 1 and 2) having round end portions 94 and 95 (Figs. 2 and 6) forming journals that are rotatable in bearings formed in center bracket 35 and in a bushing 96 which projects through and is secured in a bracket 97 (Figs. 3, 5 and 6) bolted to the adjacent end bracket 32. Bar 93 extends through a corresponding square opening formed in the pivot sleeve 41 of one of the foot clamp operating levers 39 so that said bar will be rocked by said sleeve in opposite directions when the foot clamp 49 is lowered and raised by said lever into and out of engagement with the top of the pile as hereinbefore described. Fixed on bar 93 adjacent bracket 97 is a forwardly extending arm 98 (Figs. 3, 5 and 6) having journalled thereon a roller 99 adapted to engage curved low and high cam surfaces 100 and 101, respectively, formed on the rear face of a flat circular ring sector 102. The curvature of the front face of sector 102, as well as the curvatures of the low and high cam surfaces 100, 101, are true radii with respect to the axis of rotation of bar 93.

Sector 102 constitutes the controlling member for the pile elevator and is pivotally mounted at 103 on one arm 104 of a lever 105 provided with an upwardly extending arm 106. Lever 105 is pivotally mounted on the projecting end of bushing 96 between bracket 97 and arm 98 (Fig. 6). Carried in an extension 107 of bracket 97 is a stud 108 (Figs. 3 and 5) through which extends an adjusting screw 109 having threaded engagement with a stud 110 carried by arm 106 of lever 105.

Sector 102 engages one end of a plunger pin 111 (Figs. 3 and 5) slidably mounted in a bracket 112 bolted to the adjacent end bracket 32. Threaded in the other end of pin 111 is a screw 113 the head of which engages the plunger 114 of a normally open micro-switch 115. The latter is secured within a box 116 formed integral with bracket 112 and provided with a removable cover 117. Screw 113 is adjusted so that it just contacts plunger 114, and is locked in adjusted position by a lock nut 118. Micro-switch 115 is so called because the movable contacts therein require a movement of only a few thousandths of an inch in making and breaking contact, and since said switch is well known, and disclosed in the United States Patent No. 1,960,020 granted May 22, 1934, to P. K. McGall, a further description herein is thought to be unnecessary. Switch 115 and solenoid 92 have connected therewith lead wires 119 and 120, respectively, which are connected with a suitable source of electric current, and said switch and said solenoid are connected together by a lead wire 121 so that when the plunger 114 is actuated by sector 102 to close switch 115 the electric circuit for solenoid 92 will be completed.

With the construction thus described, it will be noted that the foot clamps 49 or at least one of them, in addition to serving as a sheet winding and holding device as hereinbefore described, also acts as a supply or pile height testing member or feeler through engagement thereof with the top of the pile of sheets 23. Accordingly, when the foot clamps 49 are moved toward and away from the pile into and out of engagement with the top thereof, the arm 98 and roller 99, through the described connections therefor with one of said foot clamps, will be swung downwardly and upwardly along the low cam surface 100 and toward and away from the high cam

surface 101 on sector 102. As long as the top of pile 23 is at the proper feeding level, the pile height testing foot clamp 49 will be prevented by the pile from moving downwardly a distance sufficient to enable roller 99 on arm 98 to engage the high cam surface 101 on sector 102. Switch 115 will thus remain open, and the elevator and the operating mechanism for the latter will remain stationary because the pawl carrier 61, through engagement of latch 84 with cam strap 59 will, as shown in Fig. 1, be held in its power stroke position and prevented from returning to enable pawl 71 to engage the next tooth on ratchet 72.

When the height of the pile of sheets 23 decreases through removal of sheets from the top thereof, the roller 99 on arm 98, through increased downward movement of the pile height testing foot clamp 49 is enabled to engage the high cam surface 101 on sector 102 and swing the latter slightly forward about its pivot 103, as indicated in broken lines in Fig. 3, whereupon pin 111 is moved forwardly and plunger 114 is actuated to close the contacts of switch 115 and complete the circuit to solenoid 92. The latter is then energized and draws core 91 upwardly, thereby raising latch 84 out of engagement with cam strap 59 and rendering the pawl and ratchet mechanism operative to raise the pile elevator and pile of sheets 23 thereon as hereinbefore described.

When the pile height testing foot clamp 49 is raised out of engagement with the top of pile 23, roller 99 on arm 98 is swung out of engagement with the high cam surface 101 on sector 102, whereupon the contacts of switch 115 automatically open and cause the plunger 114 to return to its original position at which time the pin 111 and sector 102 are also returned to their original positions by said plunger, and the low cam surface 100 on sector 102 is again engaged with roller 99 on arm 98. Opening of the contacts of switch 115 deenergizes solenoid 92 whereupon core 91 and latch 84 drop by gravity and the latter is again positioned in the path of return movement of cam strap 59, thus rendering the pawl and ratchet mechanism inoperative to further raise the elevator and pile of sheets 23. If the pile of sheets 23 has not been elevated sufficiently, the above described operations of the control mechanism and of the pawl ratchet mechanism are repeated upon subsequent lowering of the pile height testing foot clamp 49 until the top of the pile of sheets reaches the proper predetermined height.

The feeding level of the pile of sheets 23 may be varied as desired to accommodate different stock conditions, and this is accomplished by rotating the adjusting screw 109 which may be effected while the feeder is in operation. When screw 109 is rotated in one direction, lever 105 will be rotated in a counterclockwise direction, as viewed in Fig. 3, about its pivot 96, thereby swinging sector 102 in the same direction through an arc concentric with the axis of rotation of roller arm 98, thus positioning the high cam surface 101 on said sector nearer to roller 99 without disturbing the operating relation between said roller and sector 102 and between the latter and the plunger pin 111. Roller 99 will then engage the high cam surface 101 sooner with the result that the normal feeding level of the pile of sheets 23 will be disposed in a higher plane. When screw 109 is rotated in the opposite direction, sector 102 will be swung in a clockwise direction (Fig.

3), thereby positioning the high cam surface 101 further away from roller 99 with the result that the normal feeding level of the pile of sheets 23 will be disposed in a lower plane.

5 If it is desired to raise the pile elevator once during each cycle of operation of the feeder, as when handling thick sheets, such as, cardboard or fibre board, this may be effected by rotating adjusting screw 109 and swinging sector 102 until the high cam surface 101 is disposed within the complete arc of oscillation of roller 99 on arm 98. In this case, roller 99 will merely idle along the high cam surface 101, micro switch will be held closed by sector 102, and solenoid 92 will be continuously energized to hold latch 84 out of engagement with cam strap 59. The pawl and ratchet mechanism will then operate once during each cycle of operation of the feeder through continued rotation of cam 58 and the action of spring 62 to raise the elevator and pile of sheets as the sheets are fed one after another from the top of said pile.

10 There is thus provided a novel mechanism for controlling the operation of a pile elevator in a sheet feeder, which is simple in construction, reliable in its operation, and has relatively few moving parts, none of which has excessive movements. Further, the novel control mechanism utilizes the foot clamp as the pile height testing means or feeler, thus eliminating the necessity of providing a separate feeler and operating means therefor. Additionally, the control mechanism may be regulated while the feeder is in operation to dispose the feeding level of the pile 15 at any desired height, and may also be regulated to render the pile elevator operating mechanism effective to continuously raise the elevator and pile of sheets thereon as the sheets are fed one after another from the top of the pile.

20 Although a single embodiment of the invention has been illustrated and described in the foregoing specification, it is to be expressly understood that changes may be made therein without departing from the spirit and scope of the invention, as will now be clear to those skilled in the art. For example, the foot clamps 49 may be employed solely as foot clamps, and separate stationary blow pipes provided for winding and floating the separated sheets. Also, a duplicate 25 control mechanism may be provided at the other side of the feeder and associated with the other foot clamp whereby operation of the elevator 30 may be controlled by the pile at more than one point thereon. Additionally, the control mechanism 35 may be without modification incorporated in a "continuous" type of sheet feeder to control the movement of the supply of sheets which is in the form of a fanned-out bank of sheets, and may be associated with mechanisms other than a pawl 40 and ratchet mechanism, for example, a hydraulic mechanism for intermittently raising a pile 45 elevator and a pile of sheets thereon. For a definition of the limits of the invention, reference 50 is had primarily to the appended claims.

55 What is claimed is:

1. In apparatus of the class described having mechanism for moving a supply of sheets, the combination of means for controlling the operation of said supply moving mechanism comprising 60 a normally stationary pivotally mounted circular ring sector having a cam surface thereon, means under the control of the sheet supply through removal of sheets therefrom for swinging said sector through engagement with the cam surface thereof, and means responsive to the

movement of said sector for rendering said mechanism effective to move the sheet supply.

2. In a sheet feeder having mechanism for moving a supply of sheets, the combination of means for controlling the operation of said supply moving mechanism comprising an arm mounted for oscillation about a fixed axis, a roller journalled on said arm, a normally stationary circular ring sector provided with a low and high cam surface concentric with the axis of oscillation of said arm, means pivotally supporting said sector with its cam surfaces in the path of movement of said roller, means engaged with the supply and operable through removal of sheets therefrom for swinging said arm and moving said sector about its pivot through engagement of said roller with the high cam surface thereof, and means responsive to the movement of said sector for rendering said mechanism effective to move the sheet supply.

3. In apparatus of the type having mechanism for moving a supply of sheets, the combination of means for controlling the operation of said sheet supply moving mechanism comprising an arm mounted for oscillation about a fixed axis, a roller journalled on said arm, a normally stationary circular ring sector provided with a low and high cam surface concentric with the axis of oscillation of said arm, a lever pivotally supporting said sector with its cam surfaces in the path of movement of said roller, means engaged with the supply and operable through removal of sheets therefrom for swinging said arm and moving said sector about its pivot through engagement of said roller with the high cam surface thereof, means responsive to the movement of said sector for rendering said mechanism effective to move the sheet supply, and means for adjusting said lever and moving said sector bodily relative to said roller in a path concentric with said axis.

4. In a sheet feeder having mechanism for moving a supply of sheets, the combination of a controlled member associated with said mechanism and movable to render the latter effective and ineffective to move the sheet supply, a normally stationary movably mounted controlling member having a low and high cam surface thereon, means normally engaged with the low cam surface of the controlling member and movable gradually toward the high cam surface thereof for moving said controlling member through engagement with the high cam surface thereof, means responsive to the movement of said controlling member for moving said controlled member to render said mechanism effective, and means engaged with the supply for controlling the movement of said controlling member.

5. In sheet handling apparatus having mechanism for moving a supply of sheets, the combination of a controlled member associated with said mechanism and operable to render the latter effective and ineffective to move the sheet supply, means including a solenoid for moving said controlled member to render said mechanism effective, a normally stationary movably mounted controlling member having a low and high cam surface thereon, a normally open electric switch associated with said controlling member and connected with said solenoid, means normally engaged with the low cam surface of the controlling member and movable gradually toward the high cam surface thereof for moving said controlling member through engagement

with the high cam surface thereof to effect closing of said switch and energizing of said solenoid, and means engaged with the supply for controlling the movement of said controlling member and closing of the switch thereby.

6. In a sheet feeder having mechanism for intermittently moving a supply of sheets, the combination of means for controlling the operation of said sheet supply moving mechanism comprising a normally stationary movably mounted controlling member having a low and high cam surface thereon, a foot clamp, means for periodically moving said foot clamp into engagement with the top of said sheet supply, means normally engaged with one of said cam surfaces and movable gradually toward the other of said cam surfaces under the control of said foot clamp for moving said controlling member through engagement with said other cam surface thereof when the movement of the foot clamp into engagement with the supply exceeds a predetermined amount, and means responsive to the movement of said controlling member for rendering the sheet supply moving mechanism effective.

7. In apparatus of the type having mechanism for moving a supply of sheets, the combination of means for controlling the operation of said sheet supply moving mechanism comprising an arm mounted for oscillation about a fixed horizontal axis and having a roller journalled thereon, a normally stationary movably mounted circular ring sector provided with a low and high cam surface concentric with the axis of oscillation of said arm, a foot clamp, mechanism for periodically moving said foot clamp downwardly into engagement with the top of the sheet supply, means connecting said arm with said foot clamp operating mechanism for corresponding movement with said foot clamp whereby said roller is caused to move said sector through engagement with the high cam surface thereof when the downward movement of said foot clamp exceeds a predetermined amount, and means responsive to the movement of said sector for rendering the sheet supply moving mechanism effective.

8. In a sheet feeder having mechanism for intermittently moving a supply of sheets, the combination of means for controlling the operation of said sheet supply moving mechanism comprising an arm mounted for oscillation about a fixed horizontal axis and having a roller journalled thereon, a normally stationary circular ring sector provided with a low and high cam surface concentric with the axis of oscillation of said arm, a lever pivotally supporting said sector with its cam surfaces in the path of movement of said roller, a foot clamp, mechanism for periodically moving said foot clamp downwardly into engagement with the top of the sheet supply, means connecting said arm with said foot clamp mechanism whereby said sector will be swung about its pivot through engagement of said roller with the high cam surface thereof when the downward movement of said foot clamp exceeds a predetermined amount, means responsive to the movement of said sector for rendering said supply moving mechanism effective, and means for adjusting said lever and moving said sector bodily relative to said roller in a path concentric with said axis.

9. In sheet feeding apparatus of the type having mechanism for intermittently moving a supply of sheets, the combination of a controlled

11

member movable in one direction to provide for operation of said mechanism and movable in the opposite direction to discontinue the operation of said mechanism, means including a solenoid for moving said controlled member in said first-named direction, an arm mounted for oscillation about a fixed horizontal axis and having a roller journaled thereon, a normally stationary pivotally mounted circular ring sector provided with a low and high cam surface concentric with the axis of oscillation of said arm, a normally open switch associated with said sector and connected

5
10

12

with said solenoid, a foot clamp, mechanism for periodically moving said foot clamp downwardly into engagement with the top of the sheet supply, and means connecting said arm with said foot clamp operating mechanism for corresponding movement with said foot clamp whereby said sector will be actuated to close said switch and energize said solenoid through engagement of said roller with the high cam surface thereof when the downward movement of said foot clamp exceeds a predetermined amount.

WALTER E. SCHNEIDER.
